INTERNAL COMBUSTION ENGINE AUTOMATIC COMPRESSION RATIO VARYING MEANS

Yasusaburo Hironaka, Tsuwano-cho, Kanoashi-gu, Japan, assignor of one-half to Kenjiro Tsuneda, Kyoto, Japan

Application April 13, 1936, Serial No. 74,210

1 Claim. (Cl. 123—48)

This invention relates to an internal combustion engine which is provided with a mechanism for automatically and accurately varying the compression ratio responsive to the variation of the vacuum in the air inlet pipe or intake manifold of the engine.

The accompanying drawing illustrates a form of embodiment of this invention, in which:

Figure 1 is a longitudinal section of an internal combustion engine according to this invention;

Figure 2 is a plan in section of the controlling device; and

Figure 3 is a detail in section taken at right angle to Figure 1, showing the piston portion only.

Throughout the various figures, same reference numerals refer to same parts.

It has been well recognized that the advanced ignition or knocking phenomena, which occur during the operation of an internal combustion engine, decrease in inverse proportion to the number of revolutions of the engine and they increase in direct proportion to increase of load. Such variation directly influences the vacuum in the air inlet pipe or intake manifold of the engine, and said vacuum is directly proportional to the engine speed and is inversely proportional to the load. Consequently, in order to automatically regulate the compression ratio, it is theoretically desirable to utilize variations of said suction pressure in the air inlet pipe or intake manifold of the engine for the purpose of securing the most accurate adjustment.

This invention is based upon such principle, and aims to provide means for automatically regulating the compression ratio of an internal combustion engine by utilizing the variation of the suction pressure in the suction pipe or inlet manifold.

Referring now to the accompanying drawing, 1 designates a piston having a piston pin 2. Journaled on said pin 2 is a sleeve 3 which is eccentric to the axis of the pin 2. Said sleeve 3 is formed at its one end with a worm gear 4 which is concentric with the pin 2. At its upper end, 15 piston rod 5 is formed as an eccentric strap surrounding the eccentric sleeve 3. Meshing with the worm gear 4 is a worm shaft 6, of which the lower end is formed as a square shaft 7, and it is made slidable in axial direction through a pinion 8 mounted on a crank case 9. Said pinion 8 meshes with a toothed rack bar 10, one end of which bar carries a piston 12 in a servo-motor cylinder 11. The piston 12 is normally held in the upper position, biased outwardly by means 20 of spring 13. Adjacent an inlet port 14 of the

servo-motor cylinder 11, a valve chest 15 is formed, in which is provided a double acting controlling valve 16 adapted to control a supply pipe 17 which is connected to the combustion chamber of the engine. In said supply pipe 17 is provided a check valve which is adapted to be opened by the explosion gas when its pressure reaches a predetermined value. A discharge pipe 18 is connected near the back seat for the valve 16. At the other end, the valve stem 19 has vacuum piston 20 in a vacuum cylinder 21, and the piston 20 is normally biased by a weak spring 22 in such direction that the supply port 17 is held open. The vacuum cylinder 21 is connected through conduit 23 with the intake manifold 24 15 of the engine, so that the piston 20 is normally under the influence of the pressure in said inlet manifold.

As the pressure fluid for the servomotor above described, explosion gas from the engine cylinders is preferably employed. If necessary, however, any other pressure fluid such as compressed air, pressure water or oil may be used for the purpose. In this case, however, the air pressure or liquid pressure used for the servomotor should 25 be such as to be varied according to the explosion gas pressure.

The operation of the invention is briefly as follows: The invention comes into operation whenever the degree of vacuum in the inlet manifold 24 decreases, so that the pressure in the vacuum cylinder 21 increases progressively toward the atmospheric pressure. Then, the spring 22 becomes effective, pushing the piston 20 outwardly, and the valve 16 opens the inlet port 17, so 30 that the pressure fluid from the port 17 enters the servo-motor cylinder 11 through the port 14 and actuates the piston 12, compressing the spring 13. The pinion 8 is rotated by the toothed rack 10 forming the piston rod of said piston 12, so 35 that the square shaft 7, worm 6, worm gear 4, eccentric sleeve 3 forming the compression ratio varying mechanism are actuated, whereby the distance between the piston head and the piston pin is shortened. Thus, the compression ratio is 40 progressively decreased. On the other hand, when the load decreases and the degree of vacuum in the inlet manifold increases, increasing the difference between the pressure in the vacuum cylinder 21 and the atmospheric pressure, 45 the piston 20 therein will move in the reverse direction. Then, the controlling valve 16 closes the supply pipe 17 and establishes connection between the servo-motor cylinder and the discharge pipe 18, so that the pressure fluid in the servo- 50

motor cylinder is discharged into atmosphere, and the servo-motor piston 12 returns to the normal position under the influence of the spring 13. Thus the compression ratio is increased by the reverse action of the regulating mechanism.

While in internal combustion engine it is desirable at a decreased load to give higher compression ratio compared with that at full load, in view of the decrease of suction, it has not been possible to obtain such effect in usual Otto cycle engines in which the combustion chambers are of the fixed volume. This invention aims to provide a mechanism responsive to the suction pressure within the inlet manifold for automatically and accurately varying the compression ratio, for the purpose of always obtaining best compression ratio for various conditions of load, number of revolutions, kind of fuel, and engine temperature, etc. According to this invention, it is possible to obtain increased thermal efficiency for various loads, and particularly a considerably increased thermal efficiency at lighter load.

What I claim is:

An internal combustion engine, comprising a

servo-motor mechanism for varying the compression ratio in the engine cylinder, means responsive to and controlled by the explosion gas pressure for actuating said servo-motor, a double acting valve controlling the admission to said servo-motor of the explosion gas coming from the engine on one hand, and controlling the discharge of said explosion gas on the other hand, a vacuum cylinder connected at its one end to the intake pipe of the engine, and open to the atmosphere at the other end, a vacuum piston in said vacuum cylinder and connected for operating said double acting valve, and a weak spring normally acting upon said vacuum piston against the action of said vacuum, the arrangement being such that the controlling valve is opened to permit the admission of the explosion gas to said servo-motor as the vacuum approaches atmospheric pressure to decrease the compression, and is closed to permit discharge of said explosion gas from said servo-motor in reversed condition to increase the compression in the engine cylinder.

YASUSABURO HIRONAKA.
